United States Patent Office

Des. 211,157
Patented May 28, 1968

211,157

BOTTLE

Richard L. Platte, Ann Arbor, Mich., assignor to Hoover
Ball and Bearing Company, Salien, Mich.

Filed Aug. 3, 1966, Ser. No. 3,330

Term of patent 14 years

(Cl. D9—129)

FIG. 1

FIG. 2

The dominant features of my design reside in the portions shown in full lines.

I claim:

The ornamental design for a bottle, as shown and described.
